[57] ABSTRACT

A tool for use in threading an advancing strand through a hole comprising a body member, severing means carried by the body member, a yieldable guide carried by the body member, said guide being biased toward a first position in which it blocks engagement of a strand with the severing means and being movable toward a second position in which it permits engagement of the strand with the severing means, whereby a strand may be engaged with the guide so that tension in the strand tends to urge the guide toward its second position and when the tension in the strand is sufficiently high to overcome the biasing force of the guide, the latter moves to permit the strand to engage and be severed by the severing means.

RING THREADING TOOL

This invention concerns a tool for threading an advancing strand through a hole such as the ring of a ring and traveller wind up mechanism.

According to this invention we provide a threading tool for threading an advancing strand through a hole comprising strand severing means and a yieldable guide effective to move a strand deflected round the guide into engagement with the severing means when the tension in the strand round the guide rises to a predetermined value.

Usually when it is required to thread a strand through a hole an end of the strand is available. Sometimes however it is required to thread a strand continuously advancing between supply means and collection means through a hole between such supply means and collection means. Such a strand may be deflected through the hole by the yieldable guide of tool according to the invention and entrained in a second collection means at a point between the hole and the guide, forming a threadline travelling through the hole to the collection means and a loop round the guide and back through the hole, whereby tightening of such loop by the collection means deflects the yieldable guide, moving the loop into contact with a severing means.

For the severing means we prefer to use a single sharp cutting blade but other known severing means may be used such as two blades in acute angled contact, blades moving relatively to each other in cutting action, or hot wires or flames.

A convenient collection means is a conventional air suction gun and aspirator device, and conveniently the same suction gun may be used for the first and second collection means. The apparatus of the invention may however be used in conjunction with one or more other collection devices such as small mobile driven spindles.

One preferred embodiment of the invention will now be described by way of example with reference to the drawings accompanying the provisional specification in which

FIG. 1 is a view of the threading tool partly in section.

FIG. 2 illustrates the position of the tool of FIG. 1 in use as it is first engaged with a threadline, and

FIG. 3 illustrates the position of the tool when the threadline is about to be cut.

Referring to FIG. 1, the tool comprises a guide notch 1 in an arm 2 pivotally mounted by means of a pin 3 on one limb of a U-shaped member 4. A spring 5 urges the arm 2 into contact with a recess 6 in the other limb of the U-shaped member 4 which is mounted on a rod 8 with a handle 9. A blade 7 is attached across the limbs of member 4.

The threading tool illustrated in FIG. 1 may be used in conjunction with a suction gun collection device as illustrated in FIGS. 2 and 3. Referring to FIG. 2, a running threadline 10 is entrained with a suction gun

11 and brought above the ring 12 of a ring and traveller wind up device. The threading tool 13 is passed upwards through the ring 12 and the running threadline is entered into the guide notch 1. Referring now to FIG. 3, the threading tool is withdrawn back through the ring, forming a threadline with two acute angles, one under the tool and one over the ring. The suction gun is moved near enough to the threadline 15 between the ring and the threading tool to entrain it, creating one running threadline through the ring to the suction gun and a loop from the suction gun, round the guide notch 1 and the ring 12, and back to the suction gun. This loop tightens under the suction until it moves the yieldable guide and is cut on the blade. The two ends are then collected by the suction gun.

This method is appropriate for use with a threadline comprising continuous filaments. A threadline comprising only staple fibers has little strength before being twisted and then the tool of this invention may be used in conjunction with a suction gun which also imparts sufficient false twist to provide adequate threadline strength to permit operation of the tool before twist is imparted by the traveller.

What we claim is:

1. A tool for use in threading an advancing strand through a hole comprising a body member, severing means carried by the body member, a yieldable guide carried by the body member, said guide being biased toward a first position in which it blocks engagement of a strand with the severing means and being movable toward a second position in which it permits engagement of the strand with the severing means, whereby a strand may be engaged with the guide so that tension in the strand tends to urge the guide toward its second position and when the tension in the strand is sufficiently high to overcome the biasing force of the guide, the latter moves to permit the strand to engage and be severed by the severing means.

2. A tool as in claim 1 wherein the yieldable guide is constructed to release the strand as the guide moves toward its second position.

3. A tool as in claim 1 wherein the severing means is a cutting blade.

4. A tool as in claim 1 wherein the yieldable guide is a pivoted spring biased arm.

5. A tool as in claim 1 wherein the yieldable guide is provided with a strand-guiding notch.

6. A tool as in claim 1 wherein said body member includes an elongated rod, said severing means and said yieldable guide being carried by said rod near one end thereof.

7. A tool as in claim 6 wherein said severing means is a cutting edge facing generally in a direction along the length of the rod and wherein said guide is a pivoted arm which is spring-biased in said direction and into engagement with stop means carried by the rod.
